6 Claims. (Cl. 101—114)

ABSTRACT OF THE DISCLOSURE

This invention relates to a stencil printing device in which a stencil member surrounded by a flexible wall is brought into intimate contact with the surface being decorated by creating a vacuum in the space between the stencil and the surface, and simultaneously utilizing atmospheric pressure to transfer an inked image through the stencil, to the surface.

This invention relates to improvements in printing and decorating with a stencil, and more particularly relates to stencil printing and decorating of non-rigid surfaces, as for example the plastic containers currently in vogue in the dairy field and other segments of the food industry.

As a general statement, the printing quality on such containers is not too rigorous. However, to achieve any measure of acceptable printing on these surfaces does require intimate contact between the printing member and the surface being decorated. Because such containers are mass produced through a chemical blowing process, they do not provide a uniformly plane surface for such intimate contact to occur. In view of these limitations and requirements, coupled with the fact that from a practical point of view these containers must be printed at a fairly high rate of speed, there are but few prior art techniques which lend themselves to practical modes of decoration of such surfaces.

These prior art methods have been generally limited to conventional screen processes, thermographic transfers (e.g. heat labeling), or pasted paper labels. None of these, or other known techniques, is entirely satisfactory.

In conventional screen printing, a squeegee sliding across the stencil forces ink through it, making a print on the surface being decorated by adhesion on contact with the ink. There have been several prior art attempts to achieve similar results by employing pneumatic forces to extrude the ink through the stencil. Such pneumatic extrusion of the ink has the disadvantage, however, that because the full area of the stencil makes contact with the surface, there frequently are air pockets of trapped air which, being unable to escape, prevent local intimate contact, thereby preventing an image transfer at these points accordingly resulting in an incomplete or mottled print. Additionally, the ink not transferred at these points remains as an excess accumulation which will create smears during subsequent print transfers.

In the case of thermographic transfers and pasted paper labels, there are storage and deterioration problems in addition to using complex equipment for registration and adhesive application to the surface being decorated.

To use any of these prior art decorating processes requires that the surface being decorated be sufficiently non-yielding to resist the force necessary to transfer the decoration from the printing member to the surface. Because the surfaces of many plastic containers are inherently non-rigid, and therefore yieldable, such containers are usually pressurized with clean air (conforming to established standards, particularly in the food industry) in an attempt to render these surfaces more rigid during the printing operation. The need for this pressurization, cou-

2

pled with the cleanliness requirements of the air are obvious drawbacks.

Further, because of the large space requirements which are necessary to use these prior art printing techniques, these containers can generally only be decorated on their vertical surfaces, which is often of little value since the consumer who generally sees only the top of the container when they are stored below eye level in a side-by-side relationship cannot identify the product with ease.

This invention overcomes these above limitations by providing an apparatus and method of decorating a surface in which intimate contact between a printing stencil and the surface being decorated is achieved by employing vacuum techniques. More specifically this invention provides for the use of partial vacuum to bring a stencil member and the surface to be decorated into intimate contact with one another.

It is accordingly among the various objects of this invention to provide an apparatus and method for rapidly decorating rigid and non-rigid surfaces with a stencil.

It is a further object of this invention to provide a stencil printing process and apparatus which permits such an image or decoration to be placed on an exposed surface regardless of its attitude of orientation.

It is yet another object of this invention to provide an apparatus for stencil printing whose space requirements are only slightly larger than the total print area of the image to be transferred.

It is a still further object of this invention to provide an apparatus for stencil printing whose physical design can be varied in size from large to small with equal facility depending on the size of the desired image and whether the device is to be permanently installed or wholly portable.

These and other objects of this invention will become more apparent from the following description when taken in conjunction with the accompanying drawings in which:

FIGURE 1 is a schematic vertical cross-sectional view of the apparatus of this invention; and

FIGURE 2 is a bottom view of the device shown in FIGURE 1.

Referring now to the drawings, shown in schematic cross-sectional view in FIGURE 1 is printer 10, comprised of an open-ended, cylindrical housing 11 carrying a tautly stretched stencil 12 across its lower end. Carried within this cylindrical housing, behind the stencil, is a quantity of viscous ink 13. Though the illustration depicts housing 11 as being cylindrical in form, it is to be understood that an open-ended housing of any shape will suffice so long as it can carry a stencil attached to one end thereof. Carried on top of the mass of ink 13 is a follower 14 which is free to move with the ink level in the housing, its function being more fully explained hereinafter.

Surrounding the lower periphery of housing 11 is an elastomeric flanged seal 15 with its flanged portion 16 in sealing engagement with the outer periphery of the housing. The remaining portion of seal 15, is dimensioned so that its lower surface 15a extends somewhat beyond the surface of stencil 12 and has its body portion 15b in spaced-apart relation to the housing thereby forming an annular recess 17 therearound. Exhaust port 18 connected to a conventional vacuum pump (not shown) communicates with recess 17 through seal 15.

In operation, when elastomeric surface 15a is brought into contact with a surface 22, which is to be printed, a vacuum is withdrawn through exhaust port 18 so as to evacuate chamber 21, i.e. that volume bounded by annulus 15, stencil 12 and surface 22.

The evacuation of chamber 21 forces stencil 12 and surface 22 together, simultaneously compressing seal 15 enough to permit this contact. Concurrently with this ac-

tion, as the vacuum increases within chamber 21, atmospheric pressure acting on the surface of follower 14 is transmitted to ink mass 13 thereby forcing it through stencil 12 into intimate contact with surface 22. It is at this moment of intimate contact that the desired image is formed on the surface. It should be recognized that where ink viscosity is high enough so that the ink does not readily flow, the absence of follower 14 would permit cavitation and/or "tunneling" to occur within ink mass 13, eventually reaching the stencil, thereby rendering this device ineffective. Accordingly, as ink 13 is consumed, follower 14, riding on top of this ink as a piston, is correspondingly lowered and simultaneously scrapes the ink from the walls of housing 11 maintaining ink mass integrity.

The time necessary to cycle this apparatus for printing one image varies of course with such things, for example, as how rapidly the partial vacuum can be effected, how viscous the ink is, and the extent of seal deformation necessary to bring the stencil into contact with the surface being printed. In the illustrated embodiment the image cycle (i.e. the time for bringing the stencil and surface together, time for intimate contact therebetween and time for readmitting air to chamber 21) is approximately $\frac{1}{2}$ second; the sealing surface 15a extends approximately 3.0 mm. beyond the surface of stencil 12; and the ink has viscosity in excess of 100,000 centipoises.

In bringing about the intimate contact necessary between stencil 12 and surface 22 for a good image transfer, it is obvious that there will be relative motion taking place. This motion may comprise the surface 22 alone moving toward the stencil; the stencil 12 alone moving toward the surface 22; or both of these motions may act together in contributing to the bringing about the requisite intimate contact.

Generally, in employing this invention, ink viscosities are limited in range only to the extent that there be no spontaneous flow through the stencil, regardless of its attitude, i.e. whether face-up, or face-down, or some position in between. As to limitations of high ink viscosity, the ink must flow sufficiently to at least replace at the stencil surface what the previous print has removed.

This invention additionally envisions embodiments of apparatus which are substantially larger, or substantially smaller than that described, the latter having attributes of portability. In any of these contemplated modifications however, print surface area is of little concern to the performance of this apparatus, since effective unit pressures are independent of areas.

For illustration, this invention has been described in terms of printing on a plane surface. However, it should be noted that the decorating curvilinear and other non-planar surfaces can easily be accomplished with this device also, provided only that the stencil has sufficient "slack" or looseness to conform with the surface being decorated. The stencil conforms with the shape of such a non-planar surface on its first cycle of operation and thereafter retains the shape of this configuration because of the non-flowing characteristics of the high viscosity ink employed. In this circumstance the ink serves somewhat as a structural member of the printing apparatus by maintaining the stencil in the desired shape.

Though this disclosure describes the ink-containing housing 11, i.e. ink-package, as being rigid, it is obvious, in light of this disclosure, that such an ink-package can also be made of collapsible material, so long as that portion to which the stencil is connected remains sufficiently rigid to hold the stencil taut. In such a case if the container end is closed, follower 14 would obviously not be needed.

Further, though the flanged seal 15 has been identified

as being "elastomeric" in nature, it should be obvious, in light of the foregoing that other equivalent structures and/or materials may be suitable so long as they provide a yielding under the required vacuum influences to permit the stencil and surface being decorated to come into intimate contact.

It should also be noted that by compartmentalizing the ink housing 11, different colored inks may be employed simultaneously rendering a multi-colored image.

It will be understood that various changes in the details, materials, setups and arrangements of parts, which have been herein described and illustrated in order to explain the nature of the invention, may be made by those skilled in the art within the principle and scope of the invention as expressed in the appended claims.

I claim:

1. An apparatus for stencil printing comprising in combination:

- (a) means mounting a stencil member in operative position;
- (b) a flexible sealing member attached to said means, having a depending portion surrounding the stencil member around its periphery in spaced relation thereto forming a recess therearound; and
- (c) a vacuum source communicating with the aforementioned recess through a port means in the sealing member.

2. The apparatus of claim 1 wherein the depending portion of the flexible sealing member is in non-coplanar relation to the plane of the stencil.

3. The apparatus of claim 2 wherein the aforesaid means mounting a stencil member in operative position comprises as a unitary component therewith an ink package containing at least one color of ink.

4. The apparatus of claim 3 wherein said ink-package comprises:

- (a) a walled chamber; and
- (b) movable means coacting with said walled chamber for transmitting pressure to an ink carried therewithin.

5. The apparatus of claim 1 further comprising: a collapsible ink-package connected to said means mounting a stencil.

6. An improved stencil printing apparatus comprising:

- (a) a housing member for enclosing a quantity of viscous fluid;
- (b) a continuous flexible wall carried at one end of said housing member;
- (c) a stencil member recessed within the periphery of said continuous wall and supported by the housing member, said wall adapted for sealing engagement with a surface to be printed whereby to form a chamber between the stencil and surface;
- (d) piston means coacting with said housing member for transmitting pressure to a viscous fluid carried therewithin; and
- (e) means for withdrawing atmosphere from the aforesaid chamber causing the flexible wall to yield, thereby permitting the stencil and surface to be decorated to come into intimate contact with one another.
